UNITED STATES PATENT OFFICE.

CHARLES A. SPRAGUE, OF BIRMINGHAM, CONNECTICUT, ASSIGNOR TO THE
BASSETT'S CORSET COMPANY, OF SAME PLACE.

CORDER FOR SEWING-MACHINES.

SPECIFICATION forming part of Letters Patent No. 268,565, dated December 5, 1882.

Application filed August 18, 1882. (No model.)

To all whom it may concern:

Be it known that I, CHAS. A. SPRAGUE, of Birmingham, in the county of New Haven and State of Connecticut, have invented new Improvements in Sewing-Machine Corders; and I do hereby declare the following, when taken in connection with accompanying drawings, and the letters of reference marked thereon, to be a full, clear, and exact description of the same, and which said drawings constitute part of this specification, and represent, in—

Figure 1, a perspective view; Fig. 2, transverse section enlarged.

This invention relates to an improvement in cord-guides for sewing-machines; and it consists in a roll arranged in the presser-foot in rear of the needle, the said roll having one or more grooves corresponding to the corded surface, and also a flat surface to run upon the work in conjunction with the feed of the machine, so that the feeding is done between the said roll and the feed, and in details of construction, as more fully hereinafter described.

A represents the cloth-plate, B the presser-foot bar, and C the needle, of the sewing-machine. The presser-foot, instead of being arranged so that its under surface stands upon the work over the feed, carries a roll, D, in a slot in the foot in rear of the needle C. That part *a* of the roll directly in rear of the needle presents a flat periphery, preferably roughened or finely serrated, and stands over the feed E, so that the work passes over the work-plate and is grasped between the feed and the flat portion *a* of the roll. Hence when it advances on one side of the work the roll revolves on the opposite side. In the roll one or more annular grooves, *b*, are made, corresponding to the rib formed by the introduction of the cord, and so that while the flat part *a* of the roll runs close against the outer side of the cord *d* being introduced the rib *e* between the grooves runs on the opposite side of the same cord—that is, on the previous line of stitches made—and the next rib, *f*, runs on the next line on the opposite side of the second cord, it being understood that the ribs are produced by the grooves. The presser-foot extends forward of the rolls, and is turned down to form a tongue or guide, *h*, forward of the needle, but in substantially the same line, so as to bear against the surface of the fabric on the side of the cord next the needle, and

thus force the upper fabric, *l*, down upon the lower fabric, *m*, as seen in Fig. 2. This tongue 55 serves to hold the work down close to the needle, and so as to prevent the work lifting when the needle is drawn up. A second and like tongue, *n*, extends down from the forward end of the presser-foot upon the opposite 60 side of the cord *d* being laid, and runs upon the line of stitches on that side of the cord, as seen in Fig. 2. The cord which is being laid therefore runs between the two guides *h* *n*. By this construction of guide the lower or under 65 fabric is held flat upon the work-plate, the upper fabric drawn down upon and over the cord being laid, and because of the rotating upper feed-surface there is no inclination to pucker the work, as in case of a stationary 70 presser-foot.

It will be understood that the presser-foot must have the same yielding pressure as in ordinary presser-feet.

I claim—

1. The herein-described cord-guide for sewing-machines, consisting of the roll C, arranged in a slot in the presser-foot in rear of the needle, a portion of the said roll *a*, over the feed, flat, the adjacent surface annularly grooved corresponding to the cord to be laid, substantially as described. 75

2. The combination of the roll C, arranged in a slot in the presser-foot in rear of the needle, a portion of the said roll *a*, over the feed, 85 flat, the adjacent surface annularly grooved corresponding to the cord to be laid, with the tongue *h* on the presser-foot forward of the needle and extending down onto the work in line with the line of stitches being run, substantially as described. 90

3. The combination of the roll C, arranged in a slot in the presser-foot in rear of the needle, a portion of the said roll *a*, over the feed, 95 flat, the adjacent surface annularly grooved corresponding to the cord to be laid, with the tongue *h* on the presser-foot forward of the needle and extending down onto the work in line with line of stitches being run, and the tongue *n* on the presser-foot forward of the roll parallel with the tongue *h*, substantially as described. 100

CHARLES A. SPRAGUE.
